UNITED STATES PATENT OFFICE.

WILLIAM C. DAVIS, OF CINCINNATI, OHIO, ASSIGNOR TO HIMSELF, WILLIAM K. BOAL, AND SAMUEL P. CHESELDINE.

DESIGN FOR AGRICULTURAL BOILER.

Specification forming part of Design No. **8,047**, dated February 9, 1875; application filed January 21, 1875.
[Term of Patent 7 years.]

To all whom it may concern:

Be it known that I, WILLIAM C. DAVIS, of Cincinnati, Hamilton county, Ohio, have produced a new and ornamental Design for an Agricultural or Farmers' Boiler, of which the following is a specification:

The nature of my design is represented in the accompanying engraving, to which reference is made.

A rectangular base, A, has vertical reed-work ornamentation on sides B and fire-door C. Surmounting said base is an upper portion, D, having the form of a conic frustum and being ornamented with vertical or longitudinal reeding E, and having the molded crowning configuration of top F.

I claim as new and of my production—
The design consisting of the rectangular base A, having vertical reeding on sides B and door C, the truncated conical upper portion D, having the longitudinal reeding E, and molded or crowning top F, as shown and described.

In testimony of which invention I hereunto set my hand.

W. C. DAVIS.
